UNITED STATES PATENT OFFICE.

HELENE V. A. LORING, OF CHICAGO, ILLINOIS.

SHOULDER-BRACE.

1,209,601.

Specification of Letters Patent. Patented Dec. 19, 1916.

Application filed August 31, 1914, Serial No. 859,400. Renewed May 3, 1916. Serial No. 95,255.

To all whom it may concern:

Be it known that I, HELENE V. A. LORING, a citizen of the United States, and a resident of the city of Chicago, county of Cook, and 5 State of Illinois, have invented certain new and useful Improvements in Shoulder-Braces, of which the following is a specification.

My invention relates to improvements in 10 shoulder braces especially adapted for use by women and has for its object the provision of an improved construction of this character.

The invention consists in the combinations 15 and arrangements of parts hereinafter described and claimed.

The invention will be best understood by reference to the accompanying drawing forming a part of this specification, and in 20 which—

Figure 1 is a front view of a brace embodying my invention, Fig. 2, a rear view of the same, and Fig. 3, a side view of the same.

The preferred form of construction as 25 illustrated in the drawing comprises a waist belt 4 adapted to encircle the waist of the wearer and provided at the front with a buckle 5 for adjusting the same to position. A belt is also provided to go around the 30 chest of the wearer, said belt consisting of a rear non-elastic portion 6 and a front elastic portion 7 secured to the bottom of portion 6 at each side by stitches 8 and provided with a buckle 9 at the front for adjusting the 35 same to the wearer. An attachment is secured to the bottom of belt portion 6 centrally at the back, said attachment consisting of an upper wider loop 10 and a lower narrower loop 11. An elastic strap 12 is 40 passed through loop 11 and has its ends adjustably secured to belt 4 by means of buckles 13. Another broader strap 14 is passed through loop 10 and has its ends 45 extended over the corresponding shoulders of the wearer as shown. At the front the ends of strap 14 are extended downwardly and slightly inwardly and are stitched to the ends of belt portion 6 and the top of belt portion 7 by means of lines of stitching 50 15. The portions of the strap 14 immediately above the stitchings 15 are enlarged and outwardly bulged to accommodate the bust. From portions 16 narrower and tapering portions 17 are inclined upwardly to 55 ward the opposite shoulders and are adjustably secured to the opposite ends of said

strap by means of buckles 18. This construction constitutes a simple and efficient construction for the purpose and one which may be worn with great comfort. The enlarged portions 16 of the ends of strap 14 also serve as a brassière.

While I have illustrated and described the preferred form of construction for carrying my invention into effect, this is capable of 65 variation and modification without departing from the spirit of the invention. I, therefore, do not wish to be limited to the precise details of construction set forth, but desire to avail myself of such variations and 70 modifications as come within the scope of the appended claims.

Having described my invention what I 75 claim as new and desire to secure by Letters Patent is:

1. A shoulder brace comprising a belt adapted to encircle the chest; a loop on said belt at the back; and a strap passed through said loop and slidably therein, each end of said strap passing thence over the corresponding shoulder, thence downwardly and inwardly over the bust and attached to said belt and thence inclined upwardly toward the opposite shoulder and detachably secured to the other end of said strap, substantially as described.

2. A shoulder brace comprising a belt adapted to encircle the chest; the front part of said belt being made of elastic material; a loop on said belt at the back; and a strap passed through said loop, each end of said strap passing thence over the corresponding shoulder, thence downwardly and inwardly over the bust and attached to said belt and thence inclined upwardly toward the opposite shoulder and detachably secured to the other end of said strap, substantially as described.

3. A shoulder brace comprising a belt adapted to encircle the chest; a loop on said belt at the back; a strap passed through said loop, each end of said strap passing thence over the corresponding shoulder, thence downwardly and inwardly over the bust and attached to said belt and thence inclined upwardly toward the opposite shoulder and detachably secured to the other end of said strap; a belt encircling the waist; and a yieldable connection between said belts at the back, substantially as described.

4. A shoulder brace comprising a belt adapted to encircle the chest; the front part

of said belt being made of elastic material; a loop on said belt at the back; a strap passed through said loop, each end of said strap passing thence over the corresponding shoulder, thence downwardly and inwardly over the bust and attached to said belt and thence inclined upwardly toward the opposite shoulder and detachably secured to the other end of said strap; a belt encircling 10 the waist; and a yieldable connection between the belts at the back, substantially as described.

5. A shoulder brace comprising a belt adapted to encircle the chest, the front part 15 of said belt being made of elastic material and the rear of non-elastic material; a member secured to the bottom of said belt centrally at the back, said member comprising an upper and larger loop and a lower and 20 smaller loop; a strap passed through said upper loop, each end of said strap passing thence over the corresponding shoulder, thence downwardly and inwardly and enlarged and outwardly bulged over the bust 25 and attached to said belt and thence inclined upwardly toward the opposite shoulder and detachably secured to the other end of said strap; a belt encircling the waist; and an elastic strap passed through the lower of 30 said loops and having its ends adjustably secured to said waist belt, substantially as described.

6. A shoulder brace comprising a belt adapted to encircle the body; and a strap having a slidable connection with said belt 35 at the back, each end of said strap passing thence over the corresponding shoulder, thence downwardly and inwardly over the bust and attached to said belt and thence inclined upwardly toward the opposite shoulder 40 and detachably secured to the other end of said strap, substantially as described.

7. A shoulder brace comprising a belt adapted to encircle the chest; a strap having a slidable connection with said belt at the 45 back, each end of said strap passing thence over the corresponding shoulder, thence downwardly and inwardly over the bust and attached to said belt and thence inclined upwardly toward the opposite shoulder and 50 detachably secured to the other end of said strap; a belt adapted to encircle the waist; a strap having a slidable connection with said chest strap at the back; and an adjustable connection between the ends of said last mentioned strap and said waist belt, substantially as described.

In testimony whereof I have signed my name to this specification in the presence of two subscribing witnesses.

HELENE V. A. LORING.
